UNITED STATES PATENT OFFICE.

CHARLES W. WIPFLER, OF DETROIT, MICHIGAN, ASSIGNOR TO THE JOLIET STOVE WORKS, OF JOLIET, ILLINOIS.

DESIGN FOR A COOKING-STOVE.

SPECIFICATION forming part of Design No. 22,770, dated September 5, 1893.

Application filed August 7, 1893. Serial No. 482,615. Term of patent 3½ years.

To all whom it may concern:

Be it known that I, CHARLES W. WIPFLER, a citizen of the United States, residing at Detroit, in the county of Wayne and State of Michigan, have invented and produced a new and original Design for a Cooking-Stove, of which the following is a specification, reference being had to the accompanying drawing, showing a side elevation of a stove embodying my design.

The leading features of my design are, first, the general configuration of the stove body with the ornamental pipe bracket and warming oven, and second, the design for the doors. The design consists in the shape of the body having the flat top, terminating at the front in the curved damper plate A, the swell front door B, the hearth C, the ornamental legs, the water-back having its lower edge consisting of the double curve B', the ornamented

pipe D, and its open scroll bracket, the rectangular warming oven terminating in the scroll edging. The ornamentation of the door comprises a marginal ornamentation consisting of raised volute scrolls and central shield, having an ornamented border, and a central medallion. The shield is ornamented at each side at the top with winged dragons and a scalloped lower edge, terminating in a substantially arrow head shaped point, with radiating raised ornamental figures between.

What I claim as my invention is—

1. The design for a cooking stove, substantially as herein described and shown.
2. In a design for a cooking stove as herein shown and described, the oven door.

CHARLES W. WIPFLER.
